FOUNTAIN COMB

John E. Slaney, McKeesport, Pa., assignor to The Fountain Comb Company, McKeesport, Pa., a firm

Application August 24, 1939, Serial No. 291,759

3 Claims. (Cl. 132—13)

This invention relates to a fountain comb, the general object of the invention being to provide a comb of this nature which is of simple construction and which can be readily filled and which has simple valve means for controlling the flow of fluid from the reservoir to the teeth.

This invention also consists in certain other features of construction and in the combination and arrangement of the several parts to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a longitudinal sectional view through the comb.

Figure 2 is a section on the line 2—2 of Figure 1.

Figure 3 is a section on the line 3—3 of Figure 1.

Figure 4 is an elevation of the comb.

In these views the numeral 1 indicates an elongated tubular part which forms a reservoir 2 for the solution to be dispensed by the comb and one end of the tubular part forms a handle and the end of this handle part is open but is adapted to be closed by a plug 3 which is formed with an inner threaded part 3' for engaging internal threads in the handle part with the outer part of the plug tapered as shown at 3'' to engage a tapered outer part of the opening in the end of the handle part. Thus the plug forms a fluid-tight junction with the walls of the opening in the handle part when the plug is threaded thereinto. That part of the tubular portion which forms the back of the comb is formed with a depending flange 4 which has a socket 5 in one end and it is also formed with a longitudinally extending circular bore 6 which has one end opening into the socket 5 and its other end is provided with a tapered part and then a reduced cylindrical part which passes through the other end of the flange. A pair of elongated slots 7 is formed in the upper part of the flange and have their upper ends communicating with the reservoir and the slots 7 communicate with the bore 6 and a longitudinally extending row of holes 8 extend from the lower part of the bore through the lower edge of the flange and between the bases of the teeth 9 which depend from the lower edge of the flange. An elongated valve member 10 of circular shape

55 in cross section is located in the bore and it has

the longitudinally extending slots 11 therein which communicate with the slots 7 when the valve member is turned to a certain position and when in this position the fluid in the reservoir will pass through the slots 7, the slots 11 in the valve member and then through the holes 8 to the teeth so that this fluid will contact the scalp being combed by the device. Of course, when the valve member is in another position the slots 11 therein are out of register with the slots 7 and 10 the holes 8 and then no fluid can pass from the reservoir to said holes 8.

One end of the valve member is tapered and the end formed with a short cylindrical part as shown at 13 and a cap 14 or plug is threaded into 15 the socket 5 and has a socket in its inner end for receiving this part 13 so that the cap forms a bearing for the end 13 of the valve member. The other end of the valve member is also formed with a conical part and a long reduced cylindrical part as shown at 16, these parts fitting in the other end of the bore which is shaped to receive them as shown in Figure 1 with the part 16 extending from the end of the flange. An angle-shaped operating lever 17 has a channel part 18 20 in one end thereof through which the reduced part 16 passes and is suitably connected therewith. The other part of the lever 17 extends upwardly and has a button 19 attached thereto, this part engaging a part of the tubular portion 25 1 when the lever is pushed upon by a finger engaging the button 19. This movement of the lever opens the valve member 10 so that fluid can pass from the reservoir onto the teeth of the comb. A spring 20 has a part encircling that 30 portion of the part 16 located in the channel 18 and a part of the spring engages a portion of the tubular part 1 and another part engages the bottom of the channel, this spring acting to hold the lever in the position shown in Figure 3 with the 35 valve in closed position. By pressing upon the button 19, as before stated, the valve is moved to open position and as soon as pressure is released the spring moves the valve back to closed position. A locking screw 21 passes through a 40 threaded hole in the lever 17 and by threading the screw upwardly against a part of the member 1 the lever cannot be moved so that it will be impossible to accidentally move the lever to valve opening position. This is desirable when the device is being carried in the pocketbook or the 45 like.

Projections 8' on the lever engage the part 1 to limit movement of the lever 17 beyond valve closing position.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:—

1. A fountain comb of the class described comprising an elongated tubular member, a portion of which forms a back for the comb and another part a handle thereof, the outer end of the handle part being open for permitting fluid to be placed in the tubular part, a plug for closing said opening, a flange depending from the back part, teeth depending from the flange, a longitudinally extending bore in said flange, slots 20 extending from the bore upwardly into the tubular part, perforations extending from the bore into the spaces between the teeth, a valve of elongated form and of circular shape in cross section fitting in the bore, slots in the valve for 25 registering with the slots in the flange, a handle member connected with one end of the valve for actuating the same, spring means for holding the handle member with the valve in closed position, and locking means for holding the 30 handle member in said position.
2. A fountain comb of the class described comprising an elongated tubular part forming a reservoir with one part of the tubular portion forming a comb back and the other part a handle, the outer end of the handle being open, a plug for

closing said open end of the handle, teeth depending from the back forming part and said part having passages extending from the spaces between the teeth to the reservoir and manually operated valve means for controlling the flow of fluid through said passages, said means including an angle-shaped handle having one arm connected to the valve means and a finger engaging part on the other arm, a stop on the first arm engaging a part of the comb for stopping movement of the parts with the valve means in closed position, spring means for holding the handle member in valve closing position.

3. A fountain comb of the class described comprising a part having a reservoir therein, a flange depending from a part of said reservoir carrying part, said flange having a longitudinally extending bore therein and said device having slots extending from the bore to the reservoir and passages extending from the bore through the outer edge of the flange, an elongated valve member rotatably arranged in the bore and having slots therein, a handle member connected with one end of the valve member, said handle member being of angle form one arm connected with the valve and the other arm adapted to strike a part of the reservoir when the member is actuated to open the valve, a spring connected with the handle part for holding the valve in open position and a set screw carried by the handle part and adapted to engage the reservoir for holding the handle part in position with the valve closed.
